(57) **CLAIM**

The ornamental design for an edible ice, as shown and described.

DESCRIPTION

FIG. 1 is a top perspective view of an edible ice showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof;

FIG. 8 is a bottom perspective view thereof; and,

FIG. 9 is another top perspective view thereof, shown in an environment of use.

The broken lines shown in FIG. 9 illustrate environment that forms no part of the claimed design.
